UNITED STATES PATENT OFFICE.

WILLIAM C. KLIBER, OF FEDERALSBURG, MARYLAND.

RATCHET-WRENCH.

1,197,500.

Specification of Letters Patent.

Patented Sept. 5, 1916.

Application filed December 23, 1915. Serial No. 68,418.

To all whom it may concern:

Be it known that I, WILLIAM C. KLIBER, a citizen of the United States, residing at Federalsburg, in the county of Caroline and 5 State of Maryland, have invented certain new and useful Improvements in Ratchet-Wrenches, of which the following is a specification.

This invention appertains to ratchet tools, 10 the object in view being to provide such a tool with specially arranged coöperating jaw members so disposed that their adjustable relation with respect to each other is controlled by their longitudinal movement 15 transversely of the body of the tool.

It is further comprehended as an object to provide means for actuating the jaw members so as to cause them to more or less project from the body of said tool and simultaneously 20 regulate their adjustment whereby to enable the engagement with varying sizes of objects.

These and such other objects as may hereinafter appear are attained by the novel 25 construction, combination, and arrangement of parts to be hereinafter specifically described and claimed.

Reference will now be had to the accompanying drawings forming a part of this 30 specification, wherein:

Figure 1 is a top plan view of a device constructed in accordance with my invention; Fig. 2 is a bottom plan view thereof; Fig. 3 is a longitudinal sectional view taken 35 on the line 3—3 of Fig. 2; and Fig. 4 is a sectional view on the plane indicated by the line 4—4 of Fig. 3.

Referring to the drawing and specifically describing this device, the numeral 1 indicates the handle portion of the tool which forms the subject matter of this invention, said handle portion of the tool terminating at one end in a head holding ring 2. Seated within this ring is a revoluble head 3 having at its periphery ratchet teeth 4 with which a reversible pawl 5 normally engages. The pawl 5 is pivotally mounted at 6 and held in engaged position by a spring 7 which is so disposed as to perform its function 45 when either of its engaging extremities is in operative position with respect to the head 3. Said head is annularly grooved as indicated at 8 to receive a locking ring or equivalent locking member 9 which coacts with the 50 apertured extremity 2 of the handle to hold the head 3 in position. As will be obvious

upon reference to Fig. 2, the ring 9 is a split ring in order to enable its attachment or removal according to whether the head is to be placed on or removed from the handle 60 or body of the tool. Slidably mounted in suitable passages or openings in said head are coöperating jaw members 10, said jaw members being arranged substantially axially of the head 3 and transversely thereof 65 so as to be capable of movement in a transverse direction to more or less project laterally from the body of the tool. It will furthermore be observed that the jaw members 10 are arranged diagonally with respect 70 to each other so that as they are moved longitudinally they will approach or recede from each other according to whether they are moved outwardly or inwardly in a manner to be more clearly set forth hereinafter. 75 When moved outwardly they will obviously project farther from the body and will be adjusted toward each other to engage objects of a particular size. When moved in the reverse direction they will accommodate 80 a larger object and this simultaneous adjustment and projection is accomplished by means of an adjusting member or nut 11 having threaded connection with a threaded stem 12 projecting from one face of the head 85 3. The nut 11 adjacent its periphery contacts with the inner extremities of the jaw members 10 and has sliding contact therewith so that as the nut 11 is screwed down upon the threaded stem 12 the jaw members 90 are moved longitudinally outwardly of the head and toward each other. Surrounding the stem and seated within the recess 11 of the nut 11 is a spring 13, the extremities 95 of which are connected to the respective jaw members 10. The function of this spring is two-fold, in that it retains the jaw members from accidental displacement from the head and furthermore causes a retraction of the jaw members when the nut 11 is screwed 100 upwardly or toward the end of the stem 12. This retracting action is due to the fact that as the jaw members 10 are moved longitudinally by the adjusting nut they are caused to approach each other and to place the 105 spring under tension, which tension is relieved upon unscrewing of the nut 11, thereby causing the jaw members to move in a direction opposite to that movement imparted by screwing the nut 11 down upon the stem 110 12. Thus it follows that while the nut 11 projects the jaw members and adjusts them

toward each other, they are automatically retracted and moved away from each other (owing to their diagonal disposition in the head) when the nut 11 is adjusted in the 5 opposite direction with respect to that just referred to.

It will be understood that the jaw members 10 may be suitably grooved as indicated at 14, or may be otherwise serrated to enable 10 said jaw members to provide a proper gripping action on the object engaged thereby. The lateral projection in the manner indicated above enables the tool to be particularly useful in gripping pipes or other 15 objects which may be projecting from a wall but not projecting sufficiently for engagement by the ordinary wrenches of conventional type. In other respects the utility of the tool will be quite evident to those skilled 20 in the art to which the invention refers and it is moreover comprehended that die elements may be substituted for the jaw members and the wrench would still perform its desired function with respect to the adjustment 25 and operation of its essential parts.

It need hardly be mentioned that the head 3 is capable of being rotated by the handle 1 in either direction according to the engagement 5 of the pawl 5 therewith.

30 Slight changes in the detail construction and arrangement of the parts may be made within the spirit of the invention and the scope of the claims hereto appended.

Having thus described the invention, what 35 is claimed is:—

1. A tool of the class described comprising a handle, a revoluble head carried thereby, said head having transversely arranged, diagonal spaced passages, jaw members mov- 40 ably mounted in said passages, and adjusting means coacting with said jaw members to shift the same and thereby positively adjust the jaw members with respect to each other.

45 2. A tool of the class described comprising a handle, a revoluble head carried thereby, said head having diagonally arranged pas-

sages converging toward one side of the head, an adjusting member at the opposite side of the head, jaw members engaged by 50 the adjusting member, and means on the head for causing movement of the adjusting member toward or from the head whereby to actuate the jaw members for relative adjustment incident to movement in the diagonal 55 passages aforesaid.

3. A tool of the class described comprising a handle including a head, said head having independent passages therethrough, jaw members movable in said passages and adjustable with respect to each other incident 60 to movement therein, a relatively stationary threaded stem projecting from the head, and an adjusting nut movable on said stem toward or from the head and coöperating with 65 the jaw members to actuate the same.

4. A tool of the class described comprising a handle, a revoluble head carried thereby, jaw members mounted substantially axially of the head, and traveling means movable 70 toward or from the head and rotating against the ends of the jaw members for moving said members outwardly or inwardly of said head.

5. A tool of the class described comprising 75 a handle, a revoluble head mounted thereon, ratchet means for rotating the head, jaw members movable transversely of said head to more or less project the same, a relatively stationary threaded stem carried by said 80 head, an adjusting member mounted on said stem coöoperative with the jaw members when moved in one direction for adjusting the latter with respect to each other, spring means inclosed by the adjusting member, co- 85 acting with the jaw members and adapted to be placed under tension by the adjusting member during the movement thereof aforesaid, said spring means actuating the jaw members to retract the same into the head 90 upon movement of the adjusting member in the other direction.

In testimony whereof I affix my signature.

WILLIAM C. KLIBER.
